CLAIM

The ornamental design for a scissors, as shown and described.

DESCRIPTION

FIG. 1 is a perspective view of a scissors showing my new design;

FIG. 2 is a top plan view thereof;

FIG. 3 is a bottom view thereof;

FIG. 4 is a front elevational view thereof;

FIG. 5 is a rear elevational view thereof;

FIG. 6 is a right side elevational view thereof; and,

FIG. 7 is a left side elevational view thereof.

The portion of the scissors shown in broken lines in FIG. 5 forms no part of the claimed design.
